[57] **CLAIM**

The ornamental design for my deer scent holder, as shown and described.

DESCRIPTION

FIG. 1 is a perspective view of a deer scent holder showing my new design;

FIG. 2 is a front elevational view thereof;

FIG. 3 is a top plan view thereof;

FIG. 4 is a bottom plan view thereof;

FIG. 5 is a right side elevational view thereof, the left side being a mere image; and,

FIG. 6 is a rear elevational view thereof.
